ASSIGNORS, BY MESNE ASSIGNMENTS, TO THE COLONIAL TRUST COMPANY, TRUS-
TEE, OF PITTSBURGH, PENNSYLVANIA, A CORPORATION OF PENNSYLVANIA.

CYLINDER-HEAD FOR GAS-ENGINES.

1,083,454.

Specification of Letters Patent.

Patented Jan. 6, 1914.

Application filed March 13, 1909. Serial No. 483,131.

To all whom it may concern:

Be it known that we, EDWARD S. McCLELLAND and WILLIAM A. BOLE, citizens of the United States, and residents of Pittsburgh, 5 county of Allegheny, and State of Pennsylvania, have made a new and useful Invention in Cylinder-Heads for Gas-Engines, of which the following is a specification.

This invention relates to cylinder heads 10 and particularly to cylinder heads of motors in which an exploded charge is employed to develop power. Cylinder heads of explosion motors are usually constructed with a water chamber in which a current of 15 water is caused to circulate so as to absorb and carry off the heat generated by the exploded charges in the combustion chamber of the motor cylinder. These cylinder heads are produced by casting methods and those 20 through which the piston rods pass are generally in the form of two tubes spaced apart to form a water chamber, the respective ends of the tubes being connected by diaphragms or webs. In casting the heads, holes or 25 openings are formed in one of the diaphragms to provide means whereby the gases set up by pouring the metal in the mold may be permitted to escape from that part of the core which forms the water chamber. 30 These holes are also useful in affording means whereby the sand core for the water chamber may be removed. It has been found in practice that a head formed as just described is liable to crack or break during 35 service. In some instances the heads have been known to crack near the juncture of the inner tube with the inner diaphragm. At other times the heads have broken or pulled away at points adjacent to the cored 40 holes from which the gases and sand escape. In other words the cracking takes place at the weakest point in the head. The reason for this breaking or cracking may be explained as follows: After the casting is 45 poured, the heads are withdrawn from the flasks in order that the flasks may be used again. The cores, however, remain in the casting because they cannot conveniently be removed until the casting cools somewhat. 50 As the castings are dragged from the flasks the outer surface of the head will be exposed to the atmosphere, causing rapid radiation of heat therefrom with resultant rapid cooling of that portion. The sand core in the

water space and the core for the gland 55 through which the piston rod passes will act as insulators for the inner tube of the head and prevent its rapidly cooling. As a result of this, the outer tube will contract and become set before the inner tube can do 60 so. At a later period, when the inner tube begins to contract it finds itself confined and resisted by the outer tube to which it is tied at both ends by the diaphragms. As the inner tube continues to cool and shorten, 65 stresses are set up in both tubes, tension stresses in the cooling tube and compression stresses in the colder member. These conflicting internal stresses weaken the casting and diminish its capacity to withstand 70 stresses from without. In order to express our idea clearly, we may call the strength of the outer tube as A, and that of the inner tube B, but on account of these acting in a contradictory or opposed manner the 75 combined strength for regular duty is not A+B but rather A-B, assuming that A is greater than B. The tendency of the inner tube to pull away from the parts to which it is anchored frequently results in the head 80 cracking at a point adjacent either the inner web (that is the one within the combustion chamber) or the outer web.

One of the objects of our invention is to provide a head which will be free or practically free from internal strains or stresses due to casting or from other causes.

By constructing a casting in accordance with our invention the inner and outer tubes of the head may be permitted to contract or 90 cool independently of each other without any discordant effects.

According to one approved form of our invention the casting is made so that the inner and outer tubes are connected together by the diaphragm at one end only, the remaining ends of the tubes being free so that during the cooling process the inner and outer tubes may independently shorten as they cool and in such a manner 95 that the contraction of one tube will have 100 no deleterious effect on the other.

In order to convey a comprehensive idea of one form of our invention we have illustrated it in the accompanying drawings, in 105 which,

Figure 1 is a vertical longitudinal sectional view through a cylinder head with a

piston rod in place, the packing which is usually employed with these piston heads being merely shown diagrammatically, and, Fig. 2 is an end view of the piston head.

5 Referring now to the drawings by numerals of reference, 5 designates the outer tube of the cylinder head, 6 the inner tube thereof, and 7 the diaphragm for connecting the inner and outer tubes together and which in connection with the inner and outer tubes 10 form a water chamber 8. The casting is provided with a central opening 9 through which the piston rod 10 of any approved construction may reciprocate and the casting 15 may be provided with a seat 11 for a piston rod packing designated 12, said piston rod packing being of suitable form and material. By reference to Fig. 1 it will be observed that the outer ends of the tubes 5 and 6 are spaced away from each other by a circumferential slot or annulus.

13 designates a closing ring which is provided with a reduced portion 14 to fit into the annulus and close the slot between the 25 inner and outer tubes after the casting has been machined. The ring 13 may be fastened in place by the fastening devices 15 projecting through a flange in the ring and entering a portion of the tube 5. Similar 30 fastening devices 16 are provided for securing the ring 13 to the tube 6. The head may be attached to the cylinder 17 by fastening devices 18 which pass through the flange 19 on the cylinder head and enter the cylinder 35 17. The water chamber 8 is provided with a supply port 20 which passes through the ring 13 and into the chamber 8. A similar port 21 serves as an outlet port for the chamber 8 and this port 21 likewise is shown 40 as passing through the ring 13. The packing 12 may be secured in place by the guard ring 22 held to the ring 13 by the fastening devices 16.

When the casting is made the tubes 5 and 45 6 are cast so that one end of each tube is free of the other and as heretofore explained this enables the respective tubes to contract and expand independently of each other, and one without affecting the other. 50 In actual practice we prefer to machine the ring 13 so that the flange 23 of the ring 13 will be slightly spaced away from the flange 19 of the outer tube 5 when the flange 24 is seated on the tube 6. Then by manipulating 55 the fastening and tension devices 15 the end of the tube 5 may be drawn to the flange 23 of the ring 13 so as to put the tube 5 under slight tension and the inner tube under slight compression (whereby the

inner diaphragm 7 will be slightly dished 60 as shown in dotted lines) so that when the engine is in actual service and the outer and more exposed portion of the head, viz., tube 5, shall be heated up to a higher temperature than the inner and more protected tube 65 6, the dilation of the outer tube shall tend to remove all internal stresses in the cylinder head and the constructional elements of the cylinder head may all act in harmony to afford adequate resistance to the stresses 70 due to pressure within the cylinder. When thus constructed, if the strength of the outer wall or tube 5 is expressed by A and the strength of the inner wall or tube 6 be expressed by B, the strength of the entire head 75 is equal to A+B, and the head thus constructed and free from the internal strains due to former methods of design will be more dependable and reliable.

It is obvious that our invention may partake of forms other than that shown in the drawing without departing from the spirit of the invention or sacrificing any of the advantages thereof.

What we claim is:

1. A cylinder head casting comprising two tubes, means integral with said tubes and connecting them together, and means for putting one of the tubes under tension.

2. A cylinder head casting comprising 90 two tubes connected together at one end and spaced apart at the other, and means connecting the spaced end of one tube to the spaced end of the other tube to flex the first mentioned connection.

3. A cylinder head casting comprising an outer tube and an inner tube, a web connecting the inner end of the respective tubes, and a removable connection for the outer free ends of said tubes and for flexing said 100 web.

4. A cylinder head comprising an outer tube and an inner tube, one of these being longer than the other, a web integral with and connecting the inner ends of respective 105 tubes, the outer ends of respective tubes being free, and means for connecting the outer free ends of said tubes and to put one of said tubes under tension.

In testimony whereof, we have hereunto 110 subscribed our names this 11th day of March, 1909.

EDWARD S. McCLELLAND.
WILLIAM A. BOLE.
